DESIGN.

M. TURNER.
LADY'S BASQUE.

No. 18,323.

Patented May 15, 1888.

UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S BASQUE.

SPECIFICATION, forming part of Design No. 18,323, dated May 15, 1888.

Application filed April 20, 1888. Serial No. 271,343. Term of patent 3½ years.

To all whom it may concern:

Be it known that I, MARY TURNER, of the city, county, and State of New York, have invented and produced a new and original Design for a Pattern of a Lady's Basque; and I do hereby declare that the engraved prints accompanying this specification convey to any one accustomed to using paper patterns a clear understanding of how a garment made

up by the pattern will appear.

The design shows low-cut fronts that display a diagonal closing below the bust and a pointed girdle ornament outlining the lower edges, narrow jacket-fronts reaching nearly to the

neck on the shoulders, a pointed chemisette, 15 a close-fitting postilion back that displays an undersfolded box plait at the end of the center seam, coat-sleeves, and a standing collar.

What I claim as my invention, and desire to secure by Letters Patent, is—

20 The design for a lady's basque, as shown in the engraved prints accompanying this specification.

MARY TURNER.
